UNITED STATES PATENT OFFICE.

HEINRICH AUGUST GASSER, OF WIESBADEN, GERMANY.

COLUMN APPARATUS FOR DISTILLING, COOLING, HEATING, AND SIMILAR PURPOSES.

1,089,831.

Specification of Letters Patent. Patented Mar. 10, 1914.

Application filed October 4, 1911. Serial No. 652,742.

To all whom it may concern:

Be it known that I, HEINRICH AUGUST GASSER, a subject of the King of Prussia, and resident of Wiesbaden, in the Kingdom of Prussia, Empire of Germany, have invented certain new and useful Improvements in Column Apparatus for Distilling, Cooling, Heating, and Similar Purposes, of which the following is a specification.

This invention relates to a column apparatus for distilling, cooling, heating and similar purposes. The construction is such that the chambers within which the operation is carried on may be connected in series and that any one chamber may be cut out and removed for the purposes of cleaning or repairing without in any way interrupting or otherwise impairing the operation going on. The apparatus is so constructed that the chambers are mounted vertically in a traveling frame above each other and that the upright pipes conveying the liquid, gases and heating media to the chambers are provided with cock-controlled couplings opposite each of the chambers. In this way space is economized and stability insured, while the entire apparatus may be readily moved about in the factory, distillery or other place where it is worked.

In the accompanying drawing: Figure 1 is a side view partly in section of a column apparatus embodying my invention; Fig. 2 an end view partly in section thereof, and Fig. 3 a horizontal section taken at the top of the pipe 32.

The apparatus comprises essentially a suitable number of retorts or chambers 10 within which the distilling, cooling, heating or other process is to be carried on. These chambers are of substantially cylindrical form and they are placed in a horizontal position, vertically above one another to constitute an upright series. In order to properly support the chambers, there is provided a frame composed of corner posts 11 mounted on a truck 12 and provided with a number of spaced horizontal beams or rests 13, upon which the chambers are removably seated. The chambers communicate with a number of vertically arranged pipes, of which pipe 14 serves for the ingress and egress of the distillation or other liquid to be acted upon; pipe 15 serves for the ingress and egress of the gases or vapors that are to act on such liquid, while a pair of pipes 16, 17 serve for the ingress and egress of a heating or cool-

ing medium. The pipe 14, Fig. 1, extends along corresponding heads of chambers 10 and is connected to each of such chambers by an upper downwardly bent inlet branch 18 controlled by cock 19 and by a lower outlet branch 20 controlled by cock 21. Between each pair of branches 18, 20, pipe 14 is provided with a cock 22, so that by closing cocks 19, 21 and opening cock 22, the corresponding chamber may be cut out. Branches 18, 20 open into chamber 10 at opposite sides of a partition 23, Fig. 2, extending longitudinally through the chamber and terminating in proximity to the opposite head thereof, so that the path of the liquid within the chamber is prolonged.

The vapor pipe 15, Fig. 1, extends along the front of the apparatus and is by branches 24, Fig. 2, connected to ducts 25 that connect the top of one chamber with the bottom of the adjoining chamber. Each duct is provided with an egress cock 26 below branch 24 and with an ingress cock 27 above such branch, while a further cock 28 is provided in pipe 15, between each pair of branches. If cocks 28 are closed, and all cocks 26, 27 are opened, the vapor will flow through ducts 25 directly from chamber to chamber. If either one of the chambers is to be cut out, its lower ingress cock 27 and upper egress cock 26 are closed, while the corresponding cock 28 is opened, so that the vapor will flow around such chamber. From each duct 25, the vapor ascends into a trough 29 arranged at the bottom of the chamber next above. This trough is provided with a number of nozzles 30 opening into distributing bells 31 which are fitted into partition 23 and extend sidewise thereof. Apertures 31^a formed in both sides of the bells below the liquid level of chambers 10, serve to discharge the vapors in fine jets into the liquid, so as to effect a thorough commingling therewith.

The heating or cooling pipes 16, 17 extend along opposite sides of the apparatus and are coupled to U-shaped heating or cooling coils 32 arranged within the chambers above troughs 29. Cocks 33 control the inflow of the medium from pipe 16 into coils 32, while cocks 33^a control the outflow of the medium from the coils into pipe 17. Between each pair of chambers 10, pipes 16, 17 are further provided with cocks 34, 34^a respectively so that by opening all the cocks 33, 33^a and closing alternate or staggering cocks 34, 34^a, the

heating or cooling medium will flow through the entire series of the chambers. If either one of the chambers is to be cut out, its cocks 33, 33^a are closed and the previously closed cock 34 or 34^a located directly therebelow, is opened as will be readily understood.

The liquid to be distilled enters top of pipe 14, the cocks 22 of which are normally closed and will by top cock 19 and branch 18 enter the uppermost retort 10 at one side of partition 23. As the latter does not extend up to the opposite retort-head, the liquid will flow around the partition, and will accumulate within the retort, until it can by the top cock 21 be returned to pipe 14. As the cock 22 next below is also closed, the liquid will rise in pipe 14, until it is admitted by the next cock 19 and branch 18 into the second retort, within which the above described operation is repeated. From the second retort, the liquid flows into the third retort, fills the same up to the level of its outlet cock 21 and again enters pipe 14, this operation being repeated for each of the retorts.

For starting or maintaining the distillation, a heat or cold carrier, such as water-vapor, fire gas or a refrigerating mixture is introduced at the upper end of pipe 16, the topmost cock 34 of which is closed during normal operation. If say, steam is used as a heating medium, it will through cock 33 of pipe 16 flow into the U shaped heating and cooling coil 32 and after having passed through the same, will enter into pipe 17 by cock 33^a. The upper end of pipe 17 being closed, while its cock 34^a located directly below cock 33^a is open, the steam will descend through pipe 17, and as the next below cock 34^a is closed, the steam will through cock 33^a enter the coil 32 of the next higher retort, from whence it will through cock 33 of pipe 16 enter the latter. As, of two opposite cocks 34, 34^a of pipes 16, 17, one of said cocks will be open while the other cock is closed, the steam entering pipe 16 will encounter an upper closed cock, and a lower open cock, so that it can by the next cock 33 of pipe 16, enter the heating coil 32 of the third retort. The steam will in similar manner flow through the remainder of the retorts, and the lower ends of pipes 16, 17 until it is finally discharged through one of said pipes, or is mixed as a condensate with the distillation liquid contained in the bottom retort. This latter action may be desirable for some distillation liquids, if say live steam is used as a heat carrier. The distillate emanating from the heated distillation liquid in the form of gases and vapors, emerges at the upper end of pipe 15, the cocks 28 of which are normally closed. The gases and vapors of the bottom retort, enter successively through cock 26, duct 25 and

cock 27 the trough of the next higher retort, in which they are divided and pass through nozzles 30 into the bells 31 through the apertures 31^a of which they pass into the distillation liquid, partly surrounding said bells. The resulting distillate rises in the form of gases and vapors into the trough of the next higher retort and here passes through the phases described, the operation being repeated at each of the remaining retorts until the thoroughly enriched distillate of the top retort is discharged through pipe 15. If say the central retort is to be cut out for any reason, the corresponding cocks 19 and 21 of pipe 14 are closed, while the intermediate cock 22 is opened, so also the two cocks 33, 33^a between said retort and pipes 16, 17 are closed, while the two lower cocks 34, 34^a of said pipes are reversed. Finally the corresponding cock 28 of pipe 15 is opened and cocks 26, 27 are closed. In this way, the distillation liquid as well as the heating or cooling medium and the distillate can freely circumvent the central retort, so that the distillation may be carried on unobstructed in the remaining retorts. By uncoupling the central retort, it can together with the corresponding section of pipe 17 be laterally withdrawn without disturbing the operation going on in the other retorts.

It will be seen that by the means described, either chamber may be readily cut out without interfering with the proper operation of the other chambers.

The apparatus is economical in use, may be readily wheeled about, and occupies a minimum amount of space.

I claim:

1. A column apparatus comprising an upright frame, a plurality of rests carried thereby and arranged vertically above one another, a plurality of chambers removably supported on said rests, vertical pipes, means for connecting said pipes to the chambers, and cocks in said connecting means, whereby any one of the chambers may be disconnected from said pipes.

2. A column apparatus comprising a truck, an upright frame mounted thereon, a plurality of rests carried thereby and arranged vertically above one another, a plurality of chambers removably supported on said rests, vertical pipes, means for connecting said pipes to the chambers, and cocks in said connecting means, whereby any one of the chambers may be disconnected from said pipes.

3. A column apparatus comprising an upright frame, a plurality of rests carried thereby and arranged vertically above one another, a plurality of chambers removably supported on said rests, troughs at the bottom of the chambers, nozzles extending upwardly therefrom, apertured bells communicating with the nozzles, longitudinal

partitions above the troughs, an upright liquid pipe having cock-controlled connections with each of the chambers at opposite sides of the partitions, cock-controlled vapor ducts connecting the top of one chamber with the trough of the adjoining chamber, an upright cock-controlled vapor pipe connected to the ducts, whereby any one chamber may be uncoupled from the liquid pipe and vapor pipe, heating or cooling coils

within the chambers, a pair of heating or cooling pipes, and cock-controlled connections between said coils and pipes.

Signed by me at Wiesbaden, Germany, this 21st day of September, 1911.

HEINRICH AUGUST GASSER.
